[57] CLAIM

The ornamental design for an oil filter gripping tool, as shown and described.

DESCRIPTION

FIG. 1 is a front elevational view of the oil filter gripping tool showing our new design, the rear view being a mirror image thereof.

FIG. 2 is a side elevational view thereof, the opposite side being a mirror image thereof;

FIG. 3 is a top plan view thereof; and

FIG. 4 is a bottom plan view thereof.

FIG. 1

FIG. 2

FIG. 3

FIG. 4
